RAY L. STINCHFIELD, OF ROCHESTER, NEW YORK, ASSIGNOR TO EASTMAN KODAK COMPANY, OF ROCHESTER, NEW YORK, A CORPORATION OF NEW YORK.

ELEMENT FOR USE IN COLOR PHOTOGRAPHY.

1,364,959.

Specification of Letters Patent. Patented Jan. 11, 1921.

Application filed February 6, 1920. Serial No. 356,588.

To all whom it may concern:

Be it known that I, RAY L. STINCHFIELD, a citizen of the United States of America, residing at Rochester, in the county of 5 Monroe and State of New York, have invented certain new and useful Improvements in Elements for Use in Color Photography, of which the following is a full, clear, and exact specification.

10 My invention relates to color photography and more particularly to photographic elements used therein. One object of my invention is to provide a photographic element which will require from 15 the operator a knowledge of only the ordinary photographic operations. A further object is to provide an element, the manipulation of which will be under easy control. Still another object is to provide an element 20 which is simple and easily registered with coöperating elements during the assembling of the final color photograph. Further objects will hereinafter appear.

In the application of Marcus C. Hopkins, 25 Serial No. 95,967, filed May 6, 1916, for method of color photography and photographic elements, and in my application, Serial No. 312,052, filed July 19, 1919, for color photography, there are disclosed photographic transparencies or prints made up 30 of two superimposed parts. These parts are derived by suitable printing, developing, fixing, etc., operations from blanks or elements, which, as articles of manufacture, 35 may be sold separately to the photographer.

The present invention is an improved modification of the element which contributes the filter areas and image sections to the upper part of the finished transparency or 40 print. By upper part I mean the portion of the final picture which is nearest the observer's eye. I have found that a thinner, more flexible and slightly more brilliant picture may be obtained if the supporting 45 means in the element be of a strong opaque material that can be stripped off of the other parts when the latter are assembled in the final picture. Referring to the accompanying drawing:

50 Figure 1 is a perspective view, on an enlarged scale, of a portion of one of my photographically sensitive elements, showing the coating partly broken away;

Fig. 2 is a fragmentary cross section, on 55 a still larger scale, of the element shown

in Fig. 1, the section being taken on a plane at right angles to the filter lines 3;

Fig. 3 is a perspective view, on an enlarged scale, of a portion of a different element embodying my invention, the coating 60 being shown as partially broken away;

Fig. 4 is a similar view of another embodiment of my invention;

Fig. 5 is an enlarged fragmentary cross section of the element shown in Fig. 4, being taken on a plane at right angles to the filter lines 31;

Fig. 6 is a perspective view, on an enlarged scale, of a still different element embodying my invention, showing the coating 70 and some of the filter lines as partially broken away;

Fig. 7 is an enlarged fragmentary cross section of the element shown in Fig. 6, taken on a plane at right angles to the filter elements 32;

Fig. 8 is a cross section, on an enlarged scale, indicating diagrammatically a method of printing on to the element shown in Fig. 1;

Fig. 9 is a cross section, on an enlarged scale, indicating diagrammatically the method of printing on to the element shown in Fig. 6;

Fig. 10 is a diagrammatic perspective 85 view, on an enlarged scale, indicating the way in which my novel upper element is assembled with the lower element to form the final picture, the opaque backing being shown in the process of removal.

Referring now to the drawing in detail, the element shown in Fig. 1 comprises an opaque support 1 which may, for example, be thick black paper or cardboard. It is preferable that this be black, so that stray 95 light rays will not be reflected back to the sensitive emulsion during printing, but my invention is not limited to a black support. Attached to the support 1, by an adhesive 2, are a series of spaced filter lines or areas 3 100 separated by clear lines or areas 4. The adhesive 2 may be, for example, gum arabic or soluble gelatin which dissolves or loses its effective adhesive properties when it becomes wet in the usual photographic baths 105 to which the element is later subjected. The filter lines 3 are of such a color that they will coöperate with the corresponding lines on the lower element, as indicated in the Hopkins and Stinchfield applications here- 110

inabove mentioned. For example, they may be red lines while the lines of the lower element may be green or vice versa. In general the lines on the elements are approximately complementary. The light sensitive layer 5 is coated over the areas 3 and 4, being attached thereto if necessary by any suitable or preferred adhesive or substratum. In the preferred embodiment of my invention, the photographic sensitive layer 5 is a silver haloid emulsion in gelatin of the kind employed on lantern slide plates or on so-called gaslight papers. One method of forming the filter areas 3 and windows 4 in suitable juxtaposition, so that they will be carried in proper relation into the final picture, is to proceed in accordance with the general process indicated in United States Patent No. 990,247, Fifield Apr. 25, 1911. Alternate sheets of colored and colorless transparent pyroxylin may be united into a block and slices cut off at right angles to the planes of the sheets, thus yielding a set of filter areas and windows of the kind shown in present Figs. 1 and 2.

In Fig. 3 is disclosed another embodiment of my invention in which the filter lines 13 are embedded in one surface of a support 40, consisting of a continuous sheet of pyroxylin, there being windows or areas 14 interspersed between the lines 13. This screen element as a whole is attached to an opaque support 1 by an adhesive 2 and is covered by a sensitized layer 5, these elements being the same as those described in connection with Figs. 1 and 2.

In Figs. 4 and 5 I disclose a modified element comprising an opaque support 1 of the same kind of material as that indicated in connection with Fig. 1, the upper face, or rather the face which is to bear the other parts of the element, being covered with an adhesive 2, such as gum arabic or soluble gelatin. Into the adhesive-coated face of the support 1 are pressed a series of spaced colored filter lines 31 of the necessary color and transparency, these being made of pyroxylin in the preferred embodiment of my invention. They may first be formed in spaced relation upon a suitable non-yielding plate and then forced downward on to the adhesive-coated surface of the support 1 under suitable pressure. Upon the outer faces of the filter lines 31, as well as upon the intervening lines of adhesive-coated surface 36, is coated a suitable light sensitive photographic material 5, such as the lantern slide or gaslight emulsion mentioned above. Adhesion between this emulsion and the pyroxylin filter lines 31 is obtained by the usual substratum.

In Figs. 6 and 7 there is shown a further embodiment of my invention comprising an opaque support 1 on which is a layer of suitable adhesive 2 of the kind hereinabove men-

tioned and upon the latter is coated the light sensitive layer 5. Upon the latter are printed a series of spaced filter lines 32 of suitable color and transparency. When the layer or coating 5 is a gelatino-silver haloid emulsion, these lines may be printed with a material containing both pyroxylin and gelatin mixed with a suitable color and a common solvent or softener, the adjustment of the proportions and the particular colors used being within the skill of persons familiar with this art. Thus the common solvent may, for instance, be acetic ether, as set forth in United States Patent No. 550,288, Penniman, Nov. 26, 1895. This causes the printed or deposited lines 32 to adhere to the gelatin of the emulsion 5 and yet be sufficiently waterproof to retain the color during the subsequent manipulations of the element in photographic baths.

Since the general methods in which my elements are used are set forth in full in the Hopkins and Stinchfield applications hereinabove mentioned, and since the present invention relates to the element as an article of manufacture, the entire processes of making the final colored photograph will not be set forth, but I will describe the features of the printing operation and assembling operation which are peculiar to the use of the present elements.

In Fig. 8 the element shown in Fig. 1, prior to printing, has placed upon it a transparent support 6, such as glass or celluloid, bearing lines 7 equal in area and spacing to the filter lines or areas 3. These lines 7 are opaque to the light used in printing. When the sensitive layer 5 is of the silver haloid type, which is preponderantly sensitive to blue light, the lines 7 may be black or any other color except bluish, thereby being substantially opaque to blue light and thus shielding the lines of emulsion 5 which are immediately between them and the filter lines 3. Above the support 6 I place the negative 10 bearing the image layer 9. In order to avoid parallax, I preferably employ parallel light for printing, as indicated by the arrows 11. After developing and fixing, the spaces above the windows 4 will bear image sections, while the parts of the transformed layer 5 above the filter lines 3 will be translucent.

When printing upon the element shown in Figs. 6 and 7, the use of auxiliary masking lines is unnecessary, although they may, of course, be used. It is, however, more convenient to proceed as indicated in Fig. 9, the negative 10, bearing the image layer 9, being placed directly in contact with the filter lines 32. In general, this convenient method of printing may be employed whenever the filter lines 32 are substantially so colored as to be opaque to the light waves which chiefly affect the emulsion 5. Expe-

rience has shown that when filter lines which are colored red or green are employed, they are sufficiently opaque to the blue rays which chiefly affect the ordinary silver haloid 5 emulsions, thereby permitting daylight or electric light to be used in printing.

The suitably printed element may be correspondingly combined with the lower or back elements disclosed in the said Hopkins 10 and Stinchfield applications. In Fig. 10 there is shown a lower element of the kind preferred by Hopkins, comprising a translucent support 101 bearing spaced filter lines or areas 103 separated by clear spaces or 15 windows 104, carrying thereon a printed and developed layer 105.

During the fluid treating of my present elements, the adhesive 2 becomes either dissolved or tacky, so that the opaque support 20 may be readily stripped therefrom. I take advantage of this condition to remove the opaque support 1 after it has been suitably assembled with the lower portion of the finished picture, as indicated in Fig. 10. 25 The transformed layer 5 of my element is fastened as by any suitable adhesive to the image-bearing layer 105 of the lower element, the lines 3 and 4 of my element being at the necessary angle to the lines 103 30 and 104 of the lower element and the images on the upper and lower parts of the picture being in proper registry, as more fully explained in said Hopkins and Stinchfield applications. When the adhesive between the 35 image-bearing layers has properly set and while the adhesive layer 2 is sufficiently yielding, the opaque backing 1 is stripped off from the filters and windows 3 and 4, thereby leaving a relatively thin and flexible 40 finished picture. When assembling my present invention with a lower element of the kind illustrated in Fig. 10, registration may be easily effected by looking through the transparent support 101. When the 45 lower element has an opaque backing, registration may be effected by proper alining or guiding marks along the edges of the upper and lower parts. Obviously the support 1 in the forms shown in Figs. 3 to 7 may 50 be similarly removed during assembling.

In the preferred form of my invention I employ an opaque support, because the latter absorbs stray light, being in proper optical contact with the other elements by 55 means of the adhesive layer 2, the index of refraction of which is sufficiently close to that of pyroxylin to effect said substantial optical contact. It thus constitutes a non-halation backing, tending to maintain the 60 purity and brilliance of the color rendering. But the final thin finished picture may be obtained, of course, if this support 1 be translucent and then finally stripped from the other portions of the element. It is apparent that a screen such as is shown in Fig. 65

1 may be more or less fragile and a stripping layer, even if translucent and devoid of anti-halation qualities, will be useful as it tends to protect the screen and hold it together properly until the finished color picture is finally assembled. Such a translucent stripping support may also be usefully employed with the lower reflecting support of the kind shown in my co-pending application mentioned above, registration being effected without the use of the well known guide marks along the edges. A transparent stripping support may also be found useful for protective purposes with the elements disclosed in the application of 80 Hopkins referred to and I consider as within the scope of my invention any such stripping element, whether or not it has all the characteristics and advantages found in my preferred embodiment.

An advantage inherent in the forms shown in Figs. 3, 6 and 7 is that in the final completed color picture, the outer or exposed layer is not the screen element which may be more or less fragile but a continuous homogeneous layer of material as of pyroxylin or gelatin.

It will, of course, be understood that the sensitive coating 5 is made continuous only for convenience in manufacture, and the 95 portions of it above or below filter lines, as the case may be, perform no distinctive photographic function, in contradistinction to the portions of said coating 5 above or below the window spaces which are transformed into image lines or sections. It will be further seen that the portions of sensitive material out of which said image sections are formed are alternated with the color filters or elements when considered with respect to the light rays, either in printing or viewing. While not in exactly the same plane, they are close to a common plane and are consequently interspersed for practical purposes in performing their functions. 100 Consequently in the element, as an article of manufacture, they bear a relation which enables them to contribute the properly located filter lines and image sections to the 105 finished picture.

Having thus described my invention, what I claim as new and desire to secure by Letters Patent is:

1. A photographic element comprising an opaque, light-absorbing support having on 120 one side thereof color filter areas interspersed with non-filter areas and photographic material sensitized to yield an opaque image.

2. A photographic element comprising a 125 support, including an opaque light-absorbing layer, having on one side thereof color filter areas interspersed with areas of photographic material sensitized to yield an opaque image.

3. A photographic element, comprising an opaque, light-absorbing support having on one side thereof separated color filter areas interspersed with areas of photographic material sensitized to yield an opaque image, all filter areas on said support being of substantially the same color.
4. A photographic element, comprising an opaque, light-absorbing support having on one side thereof both separated filter lines and light sensitive gelatino silver emulsion, all lines on said support being of substantially the same color.
5. A photographic element, comprising an opaque support having on one side thereof color filter areas interspersed with non-filter areas and photographic material sensitized to yield an opaque image, said support

being attached to said areas by an adhesive which softens in photographic baths to permit the stripping of the support from said areas. 20

6. An article of manufacture, comprising a support having on one side thereof separated color filter areas interspersed with areas of photographic material sensitized to yield an opaque image, said support being attached to one of the foregoing elements by means of an adhesive which weakens in the photographic baths sufficiently to permit 25 30 stripping off of the support from said elements.

Signed at Rochester, New York, this 2nd day of February, 1920.

RAY L. STINCHFIELD.
